UNITED STATES PATENT OFFICE.

JAMES R. PUTNAM, OF WATERBURY, CONNECTICUT, ASSIGNOR TO WATERBURY CLOCK CO., OF WATERBURY, CONNECTICUT, A CORPORATION.

TUBULAR CHIME-CLOCK.

1,225,489.

Specification of Letters Patent.

Patented May 8, 1917.

Application filed August 30, 1916. Serial No. 117,646.

To all whom it may concern:

Be it known that I, JAMES R. PUTNAM, a citizen of the United States, residing at Waterbury, in the county of New Haven 5 and State of Connecticut, have invented a new and useful Improvement in Tubular Chime-Clocks; and I do hereby declare the following, when taken in connection with the accompanying drawings and the characters of reference marked thereon, to be a full, clear, and exact description of the same, and which said drawings constitute part of this application, and represent, in—

Figure 1 a view in elevation of tubular chimes mounted in accordance with my invention and shown as located back of a time-movement in a clock-case the greater portion of which is broken away.

Fig. 2 a view in vertical section on the line 2—2 of Fig. 1.

Fig. 3 a detached perspective view of the chime-bridge.

Fig. 4 an end view of the chime-bridge on an enlarged scale.

Fig. 5 a detached perspective view of the hour-strike bridge.

My invention relates to an improvement in tubular chime clocks, the object being to augment the sound of the tubes and 30 prove its sonority and quality.

With these ends in view my invention consists in a tubular chime clock having certain details of construction and combinations of parts as will be hereinafter described and pointed out in the claim.

In carrying out my invention as herein shown, a series of tubes 3 are formed at their upper ends with transverse perforations 4 for the reception of cords 5 by means 40 of which they are individually suspended from a horizontal suspension-bar 6 notched as at 7 for the reception of the said cords, and fastened at its respective ends to the upper ends of two brackets 8 the upper ends 45 of which are secured to a sounding-board 9 constituting the back of the clock case 10 and at their lower ends to supports 11 carrying spacing-blocks 12 supporting a seat-board 13 upon which the time-movement 14 is fastened. The said time-movement may 50 be of any approved construction and is provided with a series of hammers 15 arranged in front of the respective tubes 3.

To augment the sound of the tubes 3 and

increase their sonority and the quality of 55 their tone, I employ a horizontally arranged chime-bridge 23 secured by its rear edge to the sounding-board 9 and having its rounded forward edge engaged by the suspension-cords 5 at a point between the upper ends 60 of the tubes 3 and the suspension-bar 6. The said chime-bridge 23 should be of sufficient width to place the cords 5 under tension a component of which will be exerted in pushing the bridge rearwardly against the sounding-board 9 which, under this arrangement, augments the sound of the tubes which are increased in sonority and quality of tone-production.

As shown, the hour-strike tube 16 is perforated at its upper end as at 17 for the reception of a suspension-cord 18 by means of which the tube is suspended from a bracket 19 secured to the side of the clock-case 10. For transmitting the sound of the 75 tube 16, to the sounding-board 9, I employ an hour-strike bridge 20 horizontally arranged and having its rear edge secured to the sounding-board 9. The edge of this bridge is formed with inclined slots 21 for 80 the reception of the suspension-cord 18 which is sufficiently deflected in the forward direction to cause a portion of its tension to force the bridge 20 against the sounding-board 9, whereby the sound of the hour 85 strike tube 16 is also augmented and improved. A hammer 22 operated from the time-movement 14 is provided for the hour-strike tube 16.

Of course in carrying out my invention, 90 the detailed construction and arrangement of parts may be varied from what is herein shown, my invention being characterized by the employment of a sounding-board and bridges for augmenting the sound of tubular chimes.

I claim:

In a tubular chime clock, the combination with a tube suspended by a cord, of a sounding-board, a chime-bridge interposed between the said sounding-board and cord in such manner as to place the cord under tension in the direction of the sounding-board against which the said chime-bridge is thus pressed by the weight of the tube, and a 100 hammer for striking the tube.

JAMES R. PUTNAM.
